UNITED STATES PATENT OFFICE

95,951

DESIGN FOR AN AIR-CONDITIONING CON- TROL DEVICE OR SIMILAR ARTICLE

Lucien L. Friez, Baltimore, Md., assignor to Ben-
dix Aviation Corporation, South Bend, Ind.,
a corporation of Delaware

Application April 10, 1935, Serial No. 56,287

Term of patent 14 years

To all whom it may concern:

Be it known that I, Lucien L. Friez, a citizen of the United States, residing at Baltimore, State of Maryland, have invented a new, original, and ornamental Design for Air-Conditioning Control Devices or Similar Articles, of which the following is a specification, reference being had to the accompanying drawing, forming part thereof.

In the drawing:

Fig. 1 is a front elevation of an air-conditioning control device showing the design of the present invention; and

Fig. 2 is a side elevation thereof.

The dominate features of the design are shown in full lines of the drawing while the features shown in dotted lines may take a form other than that shown without departing from the scope of the invention.

I claim:

The ornamental design for an air-conditioning control device or similar article, as shown and described.

In testimony whereof, I have hereunto signed my name.

LUCIEN L. FRIEZ.
